NURSE'S UNIFORM

Abraham Schatten, New York, N. Y.

Application September 18, 1940, Serial No. 357,221

2 Claims. (Cl. 2—93)

This invention relates to garments and similar devices, such as nurse's uniforms.

One object of the invention is to provide a device as hereinafter described having improved means forming an inconspicuous part of the back structure and adapted to afford freedom of movement of the arms of the wearer by a yielding connection for the sleeves, so arranged and coordinated that the back shall not be distorted, but to the contrary, reenforced, and so that the structure shall afford a perspiration absorbing or retarding back portion, and so that the back shall be capable of being uniformly easily starched and laundered as required.

Another object of the invention is to provide such a garment having the main portion of the back of minimum weight or thickness in accordance with the invention.

Another object of the invention is the provision of a device as set forth having relatively few and simple parts and which is inexpensive to manufacture on a quantity production basis, and is durable, reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary view in front elevation showing a device such as a nurse's uniform embodying the invention.

Fig. 2 is a back view thereof showing a left sleeve in normal position.

Fig. 3 is an inside view of the device with parts removed to show the back structure.

Figs. 4 and 5 and 6 are sectional views taken respectively on lines 4—4 and 5—5 and 6—6 of Fig. 3.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, there-

fore, is submitted merely as showing the preferred exemplification of the invention.

Referring in detail to the drawing, 10 denotes a device, such as a nurse's uniform, embodying the invention. The same may include a unitary structure comprising a waist 11, sleeves 12, a collar 13 and a skirt 14. The invention is best exemplified by a nurse's uniform for the reason that such a garment usually consists of poplin or other nonstretching material that is capable of being starched, whereas rubberized fabrics cannot be starched properly. Moreover, a nurse's uniform must be neat, well-fitting and yet comfortable, capable of a great deal of inexpensive laundering, and adapted to be made only of certain particular materials such as poplins or other cottons as above mentioned.

In such a garment, a source of difficulty arises because the well fitted uniform restricts the freedom of movement of the nurse, whose arms must be capable of easy motion through large angles in different directions. Heretofore, such movement resulted in a severe pull on the back of the garment, which thus reduced comfort and efficiency. This invention aims to overcome these difficulties.

Accordingly I provide a panelled back 15 including a central panel 16 and side panels 17, extending from the collar 13 to the waist belt 18. This back is, however, free ended at opposite sides, preferably the panels 17 each consisting of two mutually stiffening sections 19, 20 interconnected as by a marginal seam 21 and connected to the center panel 16 as by seams 22.

The inner panels 20, moreover, permit the gussets hereinafter described to be connected thereto for yieldability and without necessitating untidy cross seams in the outside of the back. At their upper edges these panels 19, 20 are connected into the shoulder seam 23. Whereas the outer panels 19 extend down to the skirt, the inner panels 20 have their lower ends connected into a free seam 24 as hereinafter described, so that these inner panels 20 at their lowermost points are only a little below the armholes of the sleeves, shown in Figs. 3 and 6.

Also connected into the seams 22 is an elastic anchorage structure 25 for each of the sleeves 12. The structures or gussets 25 are identical, and each may include an elastic panel 26, and a non elastic panel 27. The former is connected at the top into the shoulder seam 23, at one side into the seam 22, at its bottom into the seam 24, and at its other side it is connected to the panel 27 by the seam 28. The panel 27 is connected at

the top into the shoulder seam 23, at its bottom into the seam 24 and at one side it is connected to the back of an adjacent sleeve as by a seam 29. Thus additional yieldability is afforded because the seam 24 is free except at its ends, and this seam 24 does not show outside of the garment. It will be noted that the seam 29 leads into a seam 30 that forms a part or continuation of the usual side seam of the waist, running from the waist line to the armpit, so that the panel 27 is connected into the seam 30. In Fig. 4 one of the elastic sections 26 is shown stretched to illustrate the difference in operation, and it will be seen that extending the structure 20, 27 to the armpit substantially increases the stretchability of the device and hence the freedom of action of the arms. Moreover, there is thus provided a multi layer or pocket-like structure as clearly shown in Fig. 6 for absorbing perspiration and for arresting the spread of perspiration along the back panels 19, which would render the garment untidy. Thus the device provides a combined function and purpose which is realized by one and the same structure and whereby the primary object of stretchability is greatly increased. The armpit portion of the panels 20, 27 may be denoted 31. The construction described permits the main or central part of the back to be thin and light in weight for maximum comfort.

In operation, it will be perceived that the garment provided according to my invention affords a high degree of freedom of movement of the arms without causing the sleeves to tug at the back and without restricting the rapid and comfortable movement of the arms, singly or jointly, in forward or upward directions, so that the woman or nurse may wear a neat and reasonably snug fitting garment. The above described action is rendered possible by the elasticity of the sections 26, which may be elastic in one direction or in both vertical and horizontal directions. A pull on the section of one sleeve will not affect the other sleeve, because each elastic section is connected individually. Such connection is of a reinforced nature being effected at or into the seams 22 of the back panels. Since the panels 26, 27 are also connected into the shoulder seams, wrinkling is avoided and laundering is easy. Since the sections 27 are made of the same material as the garment, they can also be starched and will present a uniform appearance when parts thereof are exposed as in Fig. 2 by the stretching of the elastic. In this regard, it will be perceived that the long connections along the seams 22 serve to reliably anchor the panels 26, 27 and hence also the armpit sections 24 and the sleeves themselves against any accidental dislocation or wrinkling upon a sudden vigorous movement or twist of the body of the wearer. The provision of the armpit section 24 also affords yieldability of the sleeve in an upward direction and serves to arrest perspiration, and at the same time this section lies smoothly against

the body. The front of the garment is conventional in structure and appearance.

I claim:

1. The herein described garment including a waist section having back and side members and sleeves and the waist section having armholes to which the sleeves are connected only at the front thereof, and a plurality of gussets inside of the garment each comprising an elastic panel and a non-elastic panel, said panels being interconnected along upright lines and each gusset being connected to the shoulder portions of the garment, the non elastic panel being connected to the sleeve at its rear edge for freedom of movement of the sleeve with the gusset yielding, the elastic panel being continuously connected to the back remote from the armhole of the adjacent sleeve, said back having inside wall members extending from the edge of the armholes and being connected to the bottom portions of the gussets at a point below the armholes, said bottom portions of the gussets being free of the back at points intermediate of the armhole and of the connection of the elastic panel with the back to thus permit upward movement of the sleeves without distortion of the back and side members.

2. A garment of the class described, including a waist section having a back member, side members and sleeves, said waist section having shoulder seams and the sleeves being directly connected to the side members but being free of the back member, the back member having a central panel and side panels interconnected along generally vertical seams, and means for elastically controlling the sleeves upon forward and upward movement thereof, including a like gusset for each sleeve within the garment and lying along the back section, each gusset being connected into the adjacent shoulder seam, each gusset comprising an inner elastic panel and an outer non elastic panel connected by an upright seam to the elastic panel, each elastic panel being connected into the adjacent one of said generally vertical seams of the back, each of said non-elastic panels being connected to the adjacent sleeve along the back thereof, the width of said sections being substantially equal to that of the side panels of the back, the back having armholes having their margins free at the back of the sleeves with the said margins being substantially at the seam connections of the sleeves and their gussets, each of said gussets including an extension to a point below the adjacent armhole of the garment, said extension being connected into a seam between the back member and the adjacent side member, the side panels having inner and outer walls, and the gussets having their lower edges connected to the inner walls and being free of the outer walls, the said inner walls being connected into said upright seams in the back and into lower edge portions of the armholes, and the outer walls forming parts of the side panels of the back.

ABRAHAM SCHATTEN.
